UNITED STATES PATENT OFFICE.

DANIEL M. WILLARD, OF BAKERSFIELD, CALIFORNIA, ASSIGNOR OF ONE-HALF TO
ALBERT J. MILLS, OF BAKERSFIELD, CALIFORNIA.

FLYING-MACHINE.

1,242,295.

Specification of Letters Patent.

Patented Oct. 9, 1917.

Application filed January 5, 1916. Serial No. 70,394.

To all whom it may concern:

Be it known that I, DANIEL M. WILLARD, a citizen of the United States, residing at Bakersfield, in the county of Kern and State 5 of California, have invented a new and useful Flying-Machine, of which the following is a specification.

An object of this invention is to facilitate control of the flying machine.

10 Another object is to effect the control by comparatively simple construction.

Another object is the production of a flying machine having maximum strength relative to its weight.

15 Another object is to facilitate ascension and descension of the machine.

Another object is to effect ascension and descension of the machine by altering the angles of the main supporting surface or

20 wing from tip to tip thereof.

Another object is to make provision for steering in all directions entirely at the front of the machine.

25 Another object is to effect the horizontal steering of the machine at the front part and to so construct the tail that unequal air pressures on its sides will operate, unless otherwise counterbalanced, to prevent the tail of the machine from being swung out of its 30 predetermined course by the greater pressure.

Other objects and advantages may appear in the subjoined detail description.

The accompanying drawings illustrate the 35 invention.

Figure 1 is a plan view of a flying machine built in accordance with this invention.

Fig. 2 is a front elevation of Fig. 1.

Fig. 3 is a perspective view of the tail.

40 Fig. 4 is an enlarged cross section on line indicated by x^4-x^4 , Fig. 1.

Fig. 5 is a side elevation from the right of Figs. 1 and 2.

Fig. 6 is an enlarged detail of the head 45 portion of the machine, the main wing being shown in ascension and descension positions in solid and dotted lines respectively.

Fig. 7 is a perspective detail of the connections between the main wing and one of 50 the ailerons.

Fig. 8 is a sectional elevation on line indicated by x^8-x^8 , Figs. 1 and 5.

There is provided a main or leading supporting surface or, as it is generally termed,

plane or wing 1, which may be continuous 55 from tip to tip of the wing to form a single plane, or, as shown in the drawings, may be in sections, forming separate and equal planes one on each side of the machine, which act in unison to raise and lower the 60 head as will appear hereinafter. There is also provided a second supporting surface or wing 2 which may be in the form of a single rear plane or following plane. The foregoing construction of a forward plane and a 65 following plane is generally known as monoplane and the drawings embody the invention in the form of the so called monoplane, but it is understood that certain features of the invention are not limited to the monoplane type but could be applicable to the so 70 called biplane or multiplane types.

The wings 1, 2 may be curved in the form of parabolas and are mounted to tilt or rock forward and backward on a longitudinally 75 extending frame 3, the wing 1 being at the head of said frame and the wing 2 being adjacent the tail end of the frame.

The wings 1, 2 may be of different sizes if desired, as shown in the drawings, and the 80 wing 1 has a forward air-receiving edge a , an air-discharging edge b and tip edges c, d , and the following wing 2 has an air-receiving edge e , an air-discharging edge f and tip edges g, h . The leading wing 1 comprises a frame 4 of tubular or other desired construction and a skin 5 on said frame, said skin being constructed of suitable material and in the instance shown being preferably thin sheet aluminum. The following plane 90 2 comprises a frame 6 of tubular or other construction and a skin 7 which may be of the same material as the fore wing and is preferably thin sheet aluminum.

Each of the wings 1, 2 is provided with a 95 transverse brace comprising an arch-shaped member 8 fastened at its ends to the upper surface of its wing and said brace also comprising vertical members 9 extending between and connected to the arch-shaped 100 member 8 and the upper surface of the wing. The wings may be otherwise braced by any well known or preferred construction.

The wings 1, 2 are bodily movable relative to the frame 3 forward and backward 105 around axes, so as to tilt the wings at greater or less angles relative to the frame 3, said axes in this instance coinciding with the

centers from which are constructed front and rear arcuate guides 10, 11 forming portions of the frame 3, the guides 10 being parallel to one another at the head of the 5 frame and the guides 11 being parallel to one another adjacent the tail end of the frame.

The wings 1, 2 are shiftably connected to the guides 10, 11 respectively, and for this 10 purpose the frame members 12, 13 of the wings 1, 2 immediately over the guides 10, 11 respectively are provided with yokes 14 fastened to said frame members.

Each yoke 14 is provided at its lower end 15 with holes 15 to receive a headed pin 16 forming the axis or shaft for a grooved wheel 17. The projecting end of each pin 16 opposite the head end is provided with a washer 18 and is provided with a cotter pin 20 so as to detachably hold the pin in place. There is a series of wheels 17 engaging the 25 under side of each front guide 10 and another series of said wheels engaging the under side of each rear guide 11. These wheels 17 are adapted to run along the guides and thus allow the wings to which they are connected to be shifted forward and backward to different positions of adjustment. To prevent any looseness or rattling between the wings and the frame and to prevent said wings from lowering toward the frame when there is not sufficient air pressure to keep them in raised position, each yoke 14 is provided with a pin 20 to 30 journal a roller 21 adapted to engage the upper side of the guide 10 or 11 as the case may be so as to prevent the wheels 17 from falling away from the guides.

It is noted that when it is desired to 40 detach the wings from the frame, as in transportation of the machine, the pins 16 are removed from the yokes 14 so that the wheels 17 may be removed, thus allowing the yokes 14 to be raised from the guides 45 10, 11.

Means are provided to move the wings 1, 2 forward and back to change their angles relative to the frame and said means will now be described.

50 The front wing frame 4 is pivoted at 22 to a rearwardly extending furcated arm 23 provided at its fork with a bearing 24 for a shaft 25 operated by a hand wheel 26, said shaft turning in another bearing 27 pivoted 55 at 28 to an inverted V-shaped adjustable arm 29 which is pivoted at 30 to brackets 31 of the frame 3. The arm 29 is provided with a detent 32 adapted to engage a notched segment 33 on one of the brackets 60 31, said detent being normally held in engagement by a spring 34 to hold the arm 29 in adjusted position and being retracted from engagement by a rod 35 operated by a handle 36. It is seen from the foregoing 65 that by moving the shaft 25 forward and

backward the leading wing 1 is shifted forward and backward.

The frame 3 is provided with a segment 37 between the brackets 31, and to said segment is pivoted at 38 a lever 39 provided with a detent, spring, operating rod and handle corresponding to the detent 32, spring 34, rod 35 and handle 36 and indicated by the same reference characters. To the lever 39 is connected an operating line 75 or lines 40 each of which passes forward and is rove around a pulley 41 on the frame, thence passes downward and is rove around a pulley 42 on the frame, thence passes rearward under front and rear pulleys 43, 44 on the frame, thence passes upward and is rove around a pulley 45 on the frame and thence passes to and is attached to the air-discharging edge of the following wing 2. Movement of the lever 39 backward 80 will shift the following wing 2 rearward and if said lever is released, said wing will be shifted forward by reason of the pull of coil springs 46, each fastened at one end to the air-receiving edge *e* of the wing and each fastened at its opposite end to the frame 3.

The shaft 25 is provided with a pulley or drum 47 turned by said shaft and engaging the intermediate portion of an operating 95 line 48 which passes downward around pulleys 49 on the frame, thence extends laterally toward both sides and is rove around pulleys 50 that are mounted on a transverse member 51 of the frame 3, thence passes upward at both sides and has its opposite ends connected to ailerons 52 hinged at 53 to the air discharging edge *b* of the leading wing. The ailerons 52 are each normally held substantially tangent to the wing at the air-discharging edge *b* by a flat spring 54 which is fastened by rivets 55 or equivalent to the upper surface of the wing 1 and which shiftably engages a U-shaped retainer 56 fastened by rivets 57 or equivalent to the upper surface of the aileron. The springs 54 act to return the ailerons 52 from the positions to which they may be adjusted by turning of the drum 47.

From the foregoing it is seen that when 115 the drum 47 is turned in clockwise direction in Fig. 8 the aileron 52 on the left will be lowered and the operating line will be slackened so that air pressure will raise the aileron on the right somewhat above normal 120 position, and it is also seen that when the hand wheel is turned counter-clockwise the aileron on the right will be lowered and the aileron on the left will be free to adjust 125 itself to positions determined by the air pressures thereagainst.

Another important feature of my invention is the freely pivoted swinging tail 58 which comprises curved side surfaces 59, 60, said surfaces diverging rearwardly from one 130

another and being connected together and forming a wedge-shaped member expanding rearwardly. The edges of the surfaces 59, 60 diverge rearwardly. The tail 58 tapers to a thin air-receiving or air-cutting edge 63, and said tail is pivoted forward of its mid-length, for instance, one-third of the distance from front to rear more or less to the frame 3, the pivot 64 extending vertically above and below the open top and bottom of the tail and engaging the tail end of said frame. The tail 58 is free to swing about the axis of the pivot 64 and requires no operating lines for the reason that lateral steering is effected by movement of the ailerons 52 and up and down steering is effected by shifting of the wings 1, 2 rearward and forward.

It is noted that but two control members are required, namely the hand wheel 26 and lever 39, thus simplifying the control to a maximum degree, both of said members being operated by hand though they may be otherwise operated if so desired.

In practice, assuming that the flying machine has ascended and is flying in a straight course, to turn the machine to one side or the other, the operator will turn the hand wheel 26 and if it be assumed, for example, that the operator wishes to turn to the right he will turn the hand wheel clockwise in Fig. 8, thus drawing down the rear edge of the left-hand aileron 52, thus causing the left hand wing to bank and, in other words, turning the machine clockwise about its longitudinal axis. This banking or turning in a clockwise direction, as is well known, causes the machine to turn to the right.

When it is desired to ascend to a level above that at which the machine is flying the operator will pull backward on the operating wheel 26 thus increasing the angle of the leading wing 1 relative to the frame, and this, as is well known, will cause the head of the machine to rise and if the angle of the following plane 2 be not increased also, the tail of the machine will follow the path of travel of the head. However, if it be desired to ascend quickly or without causing the frame of the machine to tilt at too sharp an angle relative to a plane normal to the gravitational pull, the operator will adjust the lever 39 to increase the angle of the following plane 2 relative to the frame, and such adjustment naturally will cause ascension of the tail end of the machine, thus making possible to maintain the frame on an even keel while the machine is ascending. The same is true of descension and, to cause, descending movement of the machine, the operator adjusts the wing 1 or the wings 1, 2 forward to decrease the angles of said wings relative to the frame.

I am aware that in the prior art the angles

of portions of the wings have been changed to cause banking on one side or the other and also to obtain braking action and I am also aware that in the prior art provision has been made to change the angle of the wing on one side of the machine so as to effect banking, but, as is clear from the foregoing, I obtain an entirely different effect by the change of angle of the wings from tip to tip thereof. In the instance shown the change of angle of the wings is effected by raising and lowering the air receiving edges of the wings and at the same time lowering and raising the air discharging edges of the wings, but this result may be obtained by other construction than that shown and described, though the described construction is at present preferred.

Former constructors in this art relied upon comparatively small planes supplementary to the main supporting planes for ascending and descending and manipulation of the tail was relied upon for changing the course of the machine laterally, whereas this invention provides for steering the machine mainly at the head thereof, allowing the tail in most instances to merely follow, said tail being kept behind the head by the automatic action of the freely swinging tail.

Assuming, for example, that a strong current of air strikes one side of the machine, for instance, the right hand side in Fig. 1, it is clear that the excessive pressure against the tail surface 60 at that side will swing the tail member 58 on its pivot 64 so as to direct the air-cutting edge 63 of the tail member toward the right or, as it is commonly termed, into the wind. This allows the pressure to equalize on the tail side surfaces 59, 60 to hold the tail end of the machine against being swung out of its course and thereby altering the course of the machine. Thus, the greater the inequality of air pressures against the opposite sides of the machine, the more the tendency of the tail of said machine will be to head into the wind so as to tend to overcome side drift and prevent the machine from being blown out of the course in which the operator has directed it.

It is believed that the foregoing will enable those skilled in the art to which it appertains to make and use the invention.

I claim:

1. A flying machine comprising a frame, a wing extending on both sides of the frame, means to raise and lower the air-receiving edge of said wing from tip to tip thereof relative to the frame to change the angle of said wing, ailerons hinged to the rear edge of the wing, springs to hold the ailerons in normal position, means to depress said ailerons, and a second wing connected to said frame.

2. A flying machine comprising a frame, a wing extending on both sides of the frame, means to raise and lower the air-discharging edge of said wing from tip to tip thereof relative to the frame to change the angle of said wing, ailerons hinged to the rear edge of the wing, springs to hold the ailerons in normal position, means to depress said ailerons, and a second wing connected 10 to said frame.
3. A flying machine comprising a frame, a leading wing extending on both sides of the frame at the head end thereof, means to change the angle of the leading wing 15 from tip to tip thereof to cause a change of altitude of the machine, ailerons hinged to the leading wing, means yieldingly holding said ailerons against tilting up and down, means to depress the ailerons, and a 20 following wing at the tail end of said frame.
4. A flying machine comprising a frame, wings extending on both sides of the frame, a freely swinging tail for the frame, and means to change the angles of said wings 25 from tip to tip thereof independently of one another to cause a change of altitude of the machine.
5. A flying machine comprising a frame, a freely swinging tail for the frame, and 30 front and rear supporting surfaces of independently adjustable angularity relative to the frame to change the altitude of the machine and at the same time to maintain the frame on an even keel.
- 35 6. A flying machine comprising a frame, wings extending on both sides of the frame, said wings being one behind the other and substantially in a common plane, independently operating means to raise and lower the air-receiving edges of said wings from 40 tip to tip thereof relative to said frame, and a freely swinging tail for the frame.
7. A flying machine comprising a frame, wings extending on both sides of the frame, 45 said wings being one behind the other and substantially in a common plane, independently operating means to raise and lower the air-discharging edges of said wings from tip to tip thereof relative to said frame, and a freely swinging tail for the frame.
- 50 8. A flying machine comprising a frame, wings extending on both sides of the frame, said wings being one behind the other and substantially in a common plane, independently operating means to raise and lower the air-receiving edges of said wings from tip to tip thereof relative to said frame and at the same time to lower and raise the 55 air-discharging edges of said wings from tip to tip thereof relative to said frame, and a freely swinging tail for the frame.
- 60 9. A flying machine comprising a frame, wings extending on both sides of the frame, 65 a freely swinging tail for the frame, and

means to change the angular position of said wings relative to said frame and relative to one another.

10. A flying machine comprising a frame, wings extending on both sides of the frame, 70 a freely swinging tail for the frame, means to raise and lower the air-receiving edges of one wing and at the same time to lower and raise the air-discharging edges thereof, and means operative independently of the 75 first named means to raise and lower the air-receiving edges of the other wing and at the same time to lower and raise the air-discharging edges thereof.

11. A flying machine comprising a frame, 80 wings extending on both sides of the frame, ailerons hinged to the air-discharging edge of one of said wings, a single control member operatively connected to one of said wings and to the ailerons, and a second control member operatively connected to the other of said wings.

12. A flying machine comprising a frame, wings for said frame, and a freely-swinging 90 rearwardly expanding tail pivoted rearward of its air-receiving edge to one end of the frame.

13. A flying machine comprising a frame, wings for said frame, and a freely swinging 95 tail directly operative by unequal air pressures on opposite sides of the machine to tend to prevent the rear end of the frame from being swung out of its established course.

14. A flying machine comprising a frame, 100 wings for said frame, and a freely-swinging rearwardly expanding tail pivoted rearward of its air-receiving edge to one end of the frame, said tail having curved side surfaces.

15. A flying machine comprising a frame, wings for said frame, and a freely-swinging 105 rearwardly expanding tail pivoted rearward of its air-receiving edge to one end of the frame, said tail being open at its top and bottom.

16. A flying machine comprising a frame, wings for said frame, and a rearwardly expanding transversely swinging tail pivoted rearward of its air-receiving edge to one 110 end of said frame.

17. A flying machine comprising a frame, wings for said frame, and a tail pivoted rearward of its air-receiving edge to one end of said frame, said tail comprising rearwardly diverging side surfaces.

18. A flying machine comprising a frame, wings for said frame, and a tail pivoted rearward of its air-receiving edge to one end of said frame, said tail comprising rearwardly diverging side surfaces and rearwardly diverging upper and lower edges.

19. A flying machine comprising a frame, means operative at only the head end of the frame to steer the frame from side to side, and a freely swinging rudder for the frame.

20. A flying machine comprising a frame, rigid wings movably connected to the frame, a freely swinging tail for the frame, and independently operative means to move said 5 wings.
21. A flying machine comprising a frame, wings for the frame, ailerons to steer the head end of the frame from side to side, and a freely pivoted tail adapted to swing 10 transversely relative to the frame.
22. A flying machine comprising a frame, wings extending on both sides of the frame, a freely swinging tail for the frame, means to raise the air receiving edge of one wing, 15 and means to lower the air receiving edge of the other wing independently of the first named means.
23. A flying machine comprising a frame, wings extending on both sides of the frame, 20 a freely swinging tail for the frame, means to raise the air discharging edge of one wing, and means to lower the air discharging edge of the other wing independently of the first named means.
25. 24. A flying machine comprising a frame,

wings extending on both sides of the frame, a freely swinging tail for the frame, means to raise the air receiving edge of one wing and to simultaneously lower the air discharging edge of said wing, and means to 30 lower the air receiving edge of the other wing and to simultaneously raise the air discharging edge of said other wing independently of the first named means.

25. A flying machine comprising a frame 35 having curved guides, a wing shiftably connected to some of said guides, a second wing shiftably connected to other of said guides, a freely swinging tail for the frame, means to shift the first wing along its guides, and 40 means operative independently of the first named shifting means to shift the second wing along its guides.

Signed at Bakersfield, California, this 29th day of December, 1915.

DANIEL M. WILLARD.
